CLAIM

The ornamental design for a pirate ship climber panel, as
shown and described.

DESCRIPTION

FIG. 1 is a top right front perspective view of a pirate ship
climber panel showing my new design;

FIG. 2 is a front elevational view thereof;

FIG. 3 is a left side elevational view thereof, the right side
elevational view being a mirror image;

FIG. 4 is a rear elevational view thereof; and,

FIG. 5 is a top plan view thereof, the bottom plan view being
a mirror image.
